UNITED STATES PATENT OFFICE.

ALFRED L. PIERCE, OF WALLINGFORD, CONNECTICUT.

CUT-OUT BOX.

1,132,116.

Specification of Letters Patent. Patented Mar. 16, 1915.

Application filed May 27, 1914. Serial No. 841,301.

To all whom it may concern:

Be it known that I, ALFRED L. PIERCE, a citizen of the United States, residing at Wallingford, in the county of New Haven and State of Connecticut, have invented a new and useful Cut-Out Box, of which the following is a specification.

This invention relates to a cut out box which may be easily secured to a pole or cross arm and the invention provides for the safety and protection of the consumer's service line as well as the control of the same by the service company from its own poles.

15 A further object is to provide a cut out and fuse box which is secured or securable to the cross arm of a pole in such manner that a free circulation of air may take place between the cut out box and the cross arm, 20 thus preventing the premature rotting of the cross arm.

Another object is to provide a cut out box having a front sliding door which may be secured either in open or closed position, and the construction is such that when the door is in a closed position, the box will be weather-proof and will maintain the parts housed therein in a serviceable condition.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the drawings accompanying this specification and forming a part thereof, the preferred embodiment of my invention is illustrated, in which—

Figure 1 is a front elevation of my improved cut out box, portions being broken away, the view showing the various details of construction. Fig. 2 is a longitudinal sectional view taken on the line 2—2 of Fig. 1. Fig. 3 is a bottom plan. Fig. 4 is a cross sectional view taken on the line 4—4 of Fig. 2.

Referring to the drawings in which similar reference numerals designate corresponding parts throughout the several views, a unitary receptacle 5, preferably formed of metal and suitably coated or painted to resist the weather, is provided and comprises an open front 6. The recep-

tacle 5 is designed to receive some form of electric circuit controlling or protecting device H, which may be of various types, and is in the present drawings illustrated as a fuse holder of the conventional sort.

The sides and top of the receptacle 5 are provided with a frontal flange 7, around which extends a groove or channel 8. A door 9 is slidably guided in the groove or channel 8 and is adapted to close the open front 6 of the receptacle 5 thereby to protect and house the electric device H. The door 9 has outstanding plates or fingers 10 at its lower extremity, which are spaced to define an opening 11 therebetween, into which a latch 12 is adapted to project. The latch 12 is secured to the bottom of the receptacle 5 by a pivot 13 whereby the latch may be rotated in to the opening 11 and having been sprung between the plates 10 will be held in the opening 11. The latch 12 is provided with a downwardly bent end 14, whereby the latch may be conveniently gripped and easily manipulated. The outstanding plates 10 provide a handhold whereby the door 9 may be raised or lowered.

A bracket 15, including a downwardly extending arm 16, is secured to the upper portion of the receptacle 5 by rivets 17 and is adapted to extend over and embrace the cross arm of a pole (not shown) for the securing of the cut out box thereto. The back of the receptacle 5 is provided with outstanding and longitudinally extending ribs 18 which are spaced a distance apart, and these ribs together with the arm 16 define three lines of support for the receptacle, thus compensating for any irregularities in the surface to which the receptacle is to be secured. The outstanding ribs 18 in addition to the foregoing, provide an air space between the back of the receptacle 5 and the cross arm, thus securing a free circulation of air and preventing the premature rotting or deterioration of the cross arm or other structure to which the receptacle is secured.

The side walls of the receptacle 5 are outwardly bulged as at 19 and thus provide protected and downwardly converging walls 20 through which inlet insulating bushings 21 extend. This arrangement prevents the entrance of rain or snow into the receptacle 5. Suitable outlet and insulating bushings 22 extend through the bottom wall of the receptacle.

2

Among the many advantages of the structure disclosed are the facility with which the device may be secured to a cross arm and the weather-proof characteristics of the receptacle 5. The sliding door 9 will move downwardly when the latch 12 has been released and in order to prevent the door from becoming detached from its guiding recesses 8, a set screw 23 is mounted in the door, the screw acting in the capacity of a door check by contacting with the lower end wall of the receptacle 5. Since the door is adapted to gravitate to an open position, the contents of the receptacle 5 will be accessible and the fuse plug may be removed or replaced readily. When the door 9 is in its raised and closed position, it will be practically impossible for rain, snow, or foreign material to enter the receptacle 5. Suitable holding bolts 24 may project through the rear wall of the receptacle 5 and anchor the electric controlling device H therein. In order to securely lock the nuts 26 on bolts 24, the ribs 18 are cut away as at 25 to form recesses which receive the nuts 26 and hold the same against rotation, it being possible to loosen or tighten the bolts from the interior of the receptacle.

Having thus fully described my invention, what I claim is:—

- 30 1. In a cut-out box, a receptacle provided upon its rear face with spaced, longitudinal, support-engaging ribs defining an air passage; and an angular, support-engaging bracket secured to the receptacle, the bracket comprising a depending arm extended longitudinally with respect to the ribs, the arm lying to the rear of the ribs and between the planes, defined by the ribs.
- 40 2. In a cut-out box, a receptacle having an open front; a sliding, drop door assembled with the receptacle and constituting a closure for the open front, the door being provided at its lower end with spaced fingers; and a latch pivoted to the lower end of the receptacle and adapted to be swung across the lower end of the door to assume a position between the fingers.
- 50 3. In a cut-out box, a receptacle provided upon its rear face with spaced, support engaging ribs, one of the ribs being cut away to define a recess; and a bolt and nut structure projecting into the receptacle, one element of the bolt and nut structure being lodged in the recess and being held against rotation therein.
- 60 4. A device of the class described, comprising a receptacle, two longitudinally extending ribs carried at the back of said receptacle, said ribs symmetrically spaced along the longitudinal median line of said receptacle, and means secured to the receptacle projecting to the rear of said ribs and

defining therewith a three line support for said receptacle.

5. A device of the class described, comprising a receptacle, two longitudinally extending ribs carried at the back of said receptacle, said ribs symmetrically spaced along the longitudinal median line of said receptacle, and a bracket secured to said receptacle, projecting to the rear of and extending substantially parallel to said ribs, adapted to embrace a cross arm between said ribs and bracket, providing for three line contact therewith.

6. A service box for electric circuits, comprising an open front receptacle, said receptacle provided upon its sides and top with a frontal flange with a groove extending therearound, a door slidably disposed within said groove, said door provided with outstanding spaced plates at its lower extremity, and a latch pivotally engaging said receptacle and interlocking between said spaced plates for the maintenance of said door in a raised and closed position.

7. A device of the class described, including a unitary receptacle with an open front, a frontal flange extending around the sides and top of the receptacle and provided with a groove extending therein, a door slidably mounted within said groove and provided with a door check adjacent its upper extremity, said door provided at its lower extremity with an outstanding plate, a latch pivotally secured to the receptacle co-operating with the said outstanding plate, adapted to lock said door in a raised position, and means carried by the receptacle for the securing thereof to a supporting structure.

8. A device of the class described, including a unitary receptacle with an open front, a frontal flange extending around the sides and top of the receptacle and provided with a groove extending therein, a door slidably mounted within said groove and provided with a door check adjacent its upper extremity, said door provided at its lower extremity with an outstanding plate, a latch pivotally secured to the receptacle co-operating with the said outstanding plate, adapted to lock said door in a raised position, the side walls of said receptacle outwardly flared to form downwardly converging protected surfaces, and means extending through said protected surfaces for the leading of electric wires within said receptacle.

In testimony that I claim the foregoing as my own, I have hereto affixed my signature in the presence of two witnesses.

ALFRED L. PIERCE.
